Primary Examiner — Sharon S Oum

(57)

CLAIM

The ornamental design for an air cooling fan as shown and described.

DESCRIPTION

1.1: Perspective

1.2: Front

1.3: Back

1.4: Left

1.5: Right

1.6: Top

1.7: Bottom

1.8: Perspective

FIG. 1.1 is a perspective view of an air cooling fan showing my new design;

FIG. 1.2 is a front view thereof;

FIG. 1.3 is a rear view thereof;

FIG. 1.4 is a left side view thereof;

FIG. 1.5 is a right side view thereof;

FIG. 1.6 is a top view thereof;

FIG. 1.7 is a bottom view thereof;

(Continued)

FIG. 1.8 is a perspective view thereof with a bracket in an extended state. The broken lines in the drawings illustrate portions of the air cooling fan that form no part of the claimed design.
